UNITED STATES PATENT OFFICE

115,979

DESIGN FOR A RADIO CABINET OR THE LIKE

Bernard W. Przywara, Flint, Mich.

Application June 3, 1939, Serial No. 85,337

Term of patent 7 years

To all whom it may concern:

Be it known that I, Bernard W. Przywara, a citizen of the United States, residing at Flint, in the county of Genesee and State of Michigan, have invented a new, original, and ornamental Design for a Radio Cabinet or the like, of which the following is a specification, reference being had to the accompanying drawing, forming part thereof.

I claim:

The ornamental design for a radio cabinet or the like, as shown.

BERNARD W. PRZYWARA.
